UNITED STATES PATENT OFFICE.

RICHARD RICHARDSON, OF PROVIDENCE, RHODE ISLAND.

DESIGN FOR A FRAME FOR VENTILATING-FANS.

SPECIFICATION forming part of Design No. 32,574, dated April 24, 1900.

Application filed February 5, 1900. Serial No. 4,146. Term of patent 7 years.

To all whom it may concern:

Be it known that I, RICHARD RICHARDSON, a citizen of the United States, residing at Providence, in the county of Providence and State of Rhode Island, have invented and produced a new and original Design for a Frame for Ventilating-Fans, of which the following is a specification, reference being had to the accompanying drawings.

10 Figure 1 shows a perspective drawing of the fan-frame, illustrating my design. Fig. 2 is an edge view of the frame.

A is a central ring with the two opposite sides of its interior space cut off by the lines 15 $d\ d$, and from the top, bottom, and each side of the ring A arms C C project outward and terminate in a ring or band D, which is con-

centric with the inner ring A. An outer flat ring J is set radially on the periphery of the ring or band D at the middle of its circular 20 face, forming a right angle to said face, (see Fig. 2,) and circular flat-topped projections N N are made on two opposite sides of the ring A between the arms C C.

Having thus described my invention, I 25 claim—

The design for a fan-frame substantially as shown and described.

In testimony whereof I have hereunto set my hand this 3d day of February, A. D. 1900. 30
RICHARD RICHARDSON.

In presence of—

M. E. CLEVELAND,
BENJ. ARNOLD.
